UNITED STATES PATENT OFFICE.

AUGUSTINE DAVIS, JR., OF COVINGTON, KENTUCKY, AND ARTHUR L. BETTS, OF CINCINNATI, OHIO; SAID BETTS ASSIGNOR TO SAID DAVIS.

DESIGN FOR A CAN.

Application filed December 16, 1922. Serial No. 4,610. Term of patent 7 years.

To all whom it may concern:

Be it known that we, AUGUSTINE DAVIS, Jr., and ARTHUR L. BETTS, citizens of the United States, residing, respectively, at Covington, in the county of Kenton and State of Kentucky, and at Cincinnati, in the county of Hamilton and State of Ohio, have invented a new, original, and ornamental Design for Cans, of which the following is a specification, reference being had to the accompanying drawing, forming part thereof.

The figure is a side elevation of a can, showing our new design.

We claim:

The ornamental design for a can, as shown.

AUGUSTINE DAVIS, JR.
ARTHUR L. BETTS.
